SPRING CLIP

Ernest B. Briggs, Dubuque, Iowa, assignor of one-fourth to Gladys Jolly, Flossmore, Ill., one-fourth to Irene Harris, Cincinnati, Ohio, and one-fourth to Dorothy Davis, Dubuque, Iowa

Application September 12, 1941, Serial No. 410,636

2 Claims. (Cl. 24—255)

This invention relates to spring clips, and its general object is to provide a clip that is capable of performing a dual clamping function, and for that purpose the clip includes a pair of spring pressed clamping jaws for fastening papers or the like together, or for setting up a clamping action with any article in conjunction with which the clip may be used, and one of the jaws cooperates with the spring means of the jaws for detachably holding a writing implement such as a pen or pencil against casual removal or displacement, and without interference from or with the clamping action of the jaws or the opening or closing thereof.

A further object is to provide a spring clip that is simple in construction, inexpensive to manufacture, and extremely efficient in operation, use and service.

This invention also consists in certain other features of construction and in the combination and arrangement of the several parts, to be hereinafter fully described, illustrated in the accompanying drawing and specifically pointed out in the appended claims.

In describing the invention in detail, reference will be had to the accompanying drawing wherein like characters denote like or corresponding parts throughout the several views, and in which:

Figure 1 is a rear view of my spring clip and illustrates a pencil clamped therein.

Figure 2 is an end view of Figure 1 looking toward the point of the pencil.

Figure 3 is a sectional view taken approximately on line 3—3 of Figure 1, looking in the direction of the arrows.

Figure 4 is an end view partly in section, with the pencil removed.

Figure 5 is a front view of the clip.

Figure 6 is a view of one of the jaw members, and looking toward the inner face thereof.

Figure 7 is a front view of the tubular spring member.

Figure 8 is a view of the other jaw member and looking toward the inner face thereof.

Referring to the drawing in detail, the reference numeral 1 indicates a longitudinally split tubular spring member made from a single rectangular strip of resilient sheet metal rolled transversely upon itself to provide spaced inner and outer longitudinal edges 2 and 3 respectively, and the end edge portions of the tubular member are preferably outwardly flared to provide flanges 4. The tubular member is provided with a slot 5 extending circumferentially thereof from adjacent the inner edge 2 and through the entire

front portion of the member, so that the inner end of the slot, terminates substantially diametrically opposite the outer edge 3.

The jaw members each include a flat rectangular body, and the body 6 is formed with a handle 7 extending midway the ends of one longitudinal edge thereof for disposal in the same plane with its body, while the body 8 is formed with a handle 9 that likewise extends midway the ends of one longitudinal edge thereof, but the handle 9 is bent at its juncture with the body for disposal at an angle thereto, as best shown in Figure 4.

The jaw members are normally arranged in face to face relation with each other, with the handles extending through the slot 5 and the bodies outwardly beyond the edges 2 and 3. The extending ends of the bodies are preferably beveled as shown, and the outer faces of the bodies are each provided with a groove forming seats 10 and 11 along the length thereof and adjacent their outer ends, the edge 2 of the tubular member being mounted in the seat 10, while the edge 3 is mounted in the seat 11. The handle 7 is provided with a groove that forms a seat 12 for the inner end of the slot 5, as best shown in Figure 4.

The handle 7 is preferably provided with a hole 13, so that the clip can be suspended from a nail, hook or the like, and as the handle 9 is arranged at an angle to its body 8, it will be disposed at an outward inclination relative to the handle 7, when the jaw members are arranged in normal position.

From the above description and disclosure in the drawing, it is believed that the use of my clip will be obvious, but it might be mentioned that the jaw members are moved to open position, against the action of the tubular spring member, through the medium of the handles, and the spring member not only urges and holds the jaw members to and in clamping position, but due to the arrangement of the edges 2 and 3 relative to each other, the jaw members are normally urged rearwardly for disposal of the handle 7 in bearing engagement with the inner end of the slot 5, and with said inner end mounted in the groove or seat 12, so when a writing implement such as a pencil as shown is mounted between the body 6 and the tubular member, the latter and the body 6 will set up a clamping action against the pencil and hold the same secured to the clip against casual removal or displacement, and in a manner whereby the pencil can be easily and expeditiously removed and applied with respect to the clip.

It is thought from the foregoing description that the advantages and novel features of the invention will be readily apparent.

It is to be understood that changes may be made in the construction and in the combination and arrangement of the several parts, provided that such changes fall within the scope of the appended claims.

What I claim is:

1. In a spring clip of the character described, a longitudinally split tubular spring member provided with a circumferential slot, a pair of companion jaw elements mounted transversely of the tubular member and extending through the slot and between the longitudinal edges of the tubular member, the said longitudinal edges of the tubular member being disposed in radially offset relation, an end portion of one of said jaw elements being bent to assume an outwardly diverging angle with the complementary portion of the opposite jaw elements, the major body portions of the jaw elements being yieldably urged to face to face contacting positions by the spring member and operable to open clamping positions.

2. A spring clip comprising a longitudinally split tubular spring member shaped to provide spaced inner and outer longitudinal edges and

outwardly flared ends, said member having a slot extending for approximately one-half of its circumference from adjacent said inner longitudinal edge, a pair of companion jaw members each including a flat rectangular body disposed between said edges with the latter bearing against the bodies for urging and holding the jaw members to and in clamping relation and at the end of the slot remote from said inner longitudinal edge to cooperate with the tubular member to set up a clamping action, said bodies having grooves extending longitudinally thereof and providing seats having said inner and outer longitudinal edges mounted therein, said bodies extending outwardly beyond said inner and outer longitudinal edges and having their outer edge portions beveled, handles formed on the bodies and extending through said slot, the handle of one jaw member being arranged at an angle to its body for disposal at an outward inclination relative to the handle of the other jaw member, the latter handle having a groove therein providing a seat for receiving said end of the slot, and the latter handle being provided with an opening for suspending the clip from suitable supporting means.

ERNEST B. BRIGGS.
